UNITED STATES PATENT OFFICE.

ALBERT MEADOWS AND ALVIN G. SHERMAN, OF DETROIT, MICHIGAN, ASSIGNEES TO
DETROIT VAPOR STOVE COMPANY, OF DETROIT, MICHIGAN, A CORPORATION OF
MICHIGAN.

OIL STOVE.

Application filed March 8, 1923. Serial No. 623,620.

To all whom it may concern:

Be it known that we, ALBERT MEADOWS and ALVIN G. SHERMAN, citizens of the United States, residing at Detroit, in the 5 county of Wayne and State of Michigan, have invented certain new and useful Improvements in Oil Stoves, of which the following is a specification.

This invention relates to heavy hydro- 10 carbon oil stoves and the object of the invention is to introduce an improved priming system that is permanently connected with the stove and which is capable of selectively introducing a measured quantity of priming 15 fluid to any one of the burners.

In heavy hydrocarbon or kerosene burners, which do not employ a wick for feeding the fuel, it is necessary to use a priming fluid, the priming fluid is one of the lighter 20 hydrocarbons, such as gasoline which is capable of vaporizing at room temperature. It is a well known fact that liquid hydrocarbon which will not vaporize at room temperature cannot readily be lit with a 25 match by applying the match to the surface of a quantity of the fluid, hence it is customary to preheat the burner by introducing gasoline into it, igniting this, and allowing the same to burn. This heats up the burner 30 so that when the kerosene is turned into it the kerosene will be vaporized and will start to burn.

Heretofore the customary way of handling the priming fluid has been by using a measuring cup or can so equipped as to introduce a measured quantity of fluid to any burner selected. It has also been customary to provide at the front of the stove suitable conduits or priming horns leading to each 40 burner.

It is the object of the present invention to entirely eliminate this system of priming which has obvious disadvantages in requiring the separate filling of a small can. 45 Furthermore, the can can become temporarily mislaid leading to annoyance and is also a bother having it around on the top of the stove or in other places. The invention will be better understood when a complete 50 description of it has been given.

Fig. 1 is a front elevation of a stove equipped with our improved priming system which is partially shown in dotted lines.

Fig. 2 is a plan view of a stove showing 55 the priming system.

Fig. 3 is a vertical sectional view of part of the burner showing the oil connections.

Fig. 4 is a vertical section taken on the line 4—4 of Fig. 5.

Fig. 4^A is a fragmentary detail of the top 60 of the distributing casing.

Fig. 5 is a section taken on the line 5—5 of Fig. 4.

Fig. 6 is an enlarged vertical section 65 through the indexing mechanism.

Fig. 7 is a section on the line 7—7 of Fig. 6.

Fig. 8 is a detail in perspective showing the upper parts of the distributing casing.

Fig. 9 is a section taken through the bottom of the oil reservoir. 70

Fig. 10 is a section taken on the line 10—10 of Fig. 5.

Fig. 11 is a section taken on the line 11—11 75 of Fig. 4.

In addition to the usual oil reservoir located on the back of the stove for containing the kerosene and which is here shown and designated *a*, we provide another reservoir *b* containing the priming fluid. This reservoir comprises an outside tank into which is adapted to be inserted an inner tank or cylinder *c* provided with the usual valve *d* normally maintained closed by the spring *e* but provided with a projecting stem *f* adapted 80 to contact the bottom of the outer tank *b* and thereby hold the valve *d* open when the inner tank is placed in inverted position in the outer tank. This is a well known form of oil feed used very extensively with 85 students' oil lamps.

In an oil feed of this kind the level of the oil in the outer container is maintained constantly at a low level as at *g* for the reason that as soon as the oil in the outer 90 tank rises above the level of the discharge orifice in the inner tank, a liquid seal is established and the atmospheric pressure on the outside of the liquid more than counterbalances the force of gravity tending 95 to discharge the contents of the inner tank.

We therefore employ preferably some device of this kind to maintain a constant and low level of the fluid. Connected with the 100 bottom of the outside tank is a conduit *h* which leads to the distributing casing *i*. This distributing casing is a cylinder provided at its bottom with a subended pump well *j*. This forms a pump cylinder into 110

which the pump plunger *k* can descend. This pump plunger is provided with a hollow plunger stem *m*.

Arranged around the axis of this distributing casing *i* are a plurality of cylinder reservoirs *n*. Each of these reservoirs is connected by a conduit *o* with one of the burners 10 of the stove. The burner is connected to the heavy hydrocarbon reservoir 10 *a* by the conduit 11. The reservoirs have no communication with the interior of the distributing casing except through their tops. Secured to the hollow pump stem near the top of the distributing casing is 15 a hollow goose neck *q* forming a continuation of the passage-way through the hollow stem *m*. The goose neck is formed with a suitable T coupling that can be connected with the hollow pump stem for coupling up the goose neck and also for securing the solid rod *r* to the hollow rod to 20 form the plunger rod. On the end of this plunger rod is a knob *s* and also an inverted cup or selector *t* provided with numbers 25 on the outside as shown in Fig. 4. A coil spring *u* abuts against the washer *v* and against the inside of the cup to normally hold the plunger in its uppermost position. The washer *v* is arranged between the lower 30 end of the coil spring *r* and the top of the tank and engages against a notched bushing *w* (see Fig. 6) soldered to the top of the tank. This washer is provided with suitable ribs punched out of it so as to 35 form a temporary lock to prevent the selector *t* and the handle from being rotated accidentally. However, by utilizing a slight turning effort the radial ribs of this washer will free themselves from the notches of 40 the notched disk *w*, hence the selector can be turned around to any given position. The arrangement of the numbers on the outside of the cup is so coordinated with the position of the goose neck, that for instance, when the number "3" faces the operator at the front of the stove, he knows that the goose neck is positioned above the reservoir that is connected with the burner 45 3 of the stove.

50 The operation is simple, when the selector has been turned to expose the desired numeral at the front of the stove, the operator simply presses down on the handle against the resistance of the spring *v* and the fluid in the pump well *j*. Obviously, the fluid in the pump well will be trapped by the plunger head and can only escape up through the hollow plunger rod and thence discharge through the goose neck.

55 50 Of course, it discharges through the selected reservoir and thence runs through the connections to the burner which is to be primed. By properly calculating the capacity of the pump well, obviously any given quantity 55 of fluid for the burner is thus assured, hence

the pump well, located as it is, constitutes a charge measuring device to make sure that the burner will not be flooded.

It will be evident that the student's lamp type of oil feed is not absolutely essential for the operation of a distributing system of this kind. However, with such an arrangement of the tanks as shown in Fig. 4, if the inner filling tank were not used, obviously the height of the distributing reservoirs *n* would have to be at least, if not of greater height, than the storage tank, otherwise the storage tank might be filled to the top and overflow through the distributing reservoirs. We find it advantageous 75 to use the inner filling tank, as this when it works properly, maintains a constant low level for the exposed fuel both in the storage tank and the distributing tank, hence the distance the priming fluid has to be lifted is always practically the same. This results in a more uniform charge for each burner under all conditions as leakage by the plunger head *k* will always be practically the same. 90

However, the height of the distributing reservoirs is so calculated that under no circumstances will the priming fluid overflow through these reservoirs in case the inner filling tank fails to function properly as for instance, when an air leak occurs in the upper part of the tank breaking the liquid seal, the capacity of the two tanks and the height of the reservoirs is so calculated that even should the inner filling tank discharge 95 all its contents it will not spill over the tops of the distributing reservoir. 100

Another very important feature of this system, especially in its application to a priming system of this kind, which we desire to emphasize is that it affords a low pressure gravity feed as opposed to a force feature by a pump or other source of pressure. This gravity feature is achieved with a very small head, and the consequence is 105 that there is very little pressure behind the liquid flow through the distributing line so as to require tight joints. Furthermore, the fluid does not flow into the burner channel with any considerable force so as to run 110 over the sides of the channels which are often quite shallow. This is quite an essential point in a distributing system of this kind intended for these kerosene type burners which have channel rings in the bottom 115 of the burner that are relatively shallow. With a high pressure feed the only alternative to properly supply the fuel to a shallow channel burner would be to provide a small orifice that serves as a pressure reducing medium somewhere in the conduit. 120 Orifices of this kind are always an annoyance as they very easily plug up and cause a great deal of trouble in the operation. 125 This low gravity feature secured in the 130

manner we have described obviates all this trouble and provides the requisite slow flow into the burner channel.

What we claim is:

- 5 1. In a priming system for oil stoves, the combination of a storage tank, a distributing tank provided with a pump well in the bottom thereof, a plurality of conduits for leading from the distributing tank to separate burners, a pump plunger which can be reciprocated in the pump well to force the contents there out, and means for guiding such pump well contents to any one of the conduits selected.
- 10 2. In a priming system for oil stoves, the combination of a storage tank, a distributing tank in communication therewith, a plurality of reservoirs arranged in said distributing tank, a plurality of conduits leading to separate burners connecting with said reservoirs, a pump well in the bottom of said distributing tank, and pump plunger and rod arranged to convey the contents of the pump well to any one of the selected
- 15 20 25 reservoirs when the plunger descends into the pump well.
3. In a priming system for oil stoves, the combination of a storage tank, a distributing tank, a plurality of reservoirs located in the distributing tank and open only at their tops, a plurality of conduits for leading from the reservoirs to separate burners, a pump well in the bottom of the distributing tank, and a plunger and stem, the latter having a hollow interior and provided at the top with a goose neck whereby when the plunger descends into the pump well the contents thereof are forced up through the hollow stem and goose neck and discharged into any one of the selected reservoirs.
4. In a priming system for oil stoves, the combination of a storage tank, a distributing tank in communication therewith and provided at its bottom with a pump well, a plunger and plunger stem arranged so as the former descends into the pump well it thereby exhausts the contents thereof, plunger and stem being arranged to convey
- away the exhausted contents, a plurality of conduits connectible to separate burners, said pump plunger and the pump stem being arranged to select any one of the conduits upon rotative movement of the rod and plunger, and a selector on the top of the plunger rod for indicating the conduits selected for discharge of the priming fluid from the pump well.
5. In a priming system for oil stoves, the combination of a storage tank, means therefor maintaining the level of the exposed liquid in said storage tank at a constantly low level, a distributing tank in communication with the bottom of the storage tank and in which the level of the fluid is the same as the exposed liquid in the storage tank, a plurality of distributing conduits for connecting the separate burners having communication with the interior of the distributing tank above the constant level line, and means for measuring a quantity of liquid out of the bottom of the distributing tank and lifting and selectively delivering it into any one of the distributing conduits.
6. In a priming system for oil stoves, the combination of a storage tank, an inner invertible tank which can be supported in the storage tank and which is provided with devices to maintain a given oil level in the storage tank by feeding oil from the inner tank, a separate distributing tank in communication with the bottom of the storage tank, a plurality of distributing conduits for connecting the separate burners having communication with the interior of the distributing tank above the constant level line afforded in such distributing tank by the operation of the inner tank contained within the storage tank, and means for measuring a quantity of liquid out of the bottom of the distributing tank and lifting and selectively delivering it into any one of the distributing conduits.

In testimony whereof we affix our signatures.

ALBERT MEADOWS.
ALVIN G. SHERMAN.
